(57) CLAIM

The ornamental design for a hood with brim for a garment as shown and described.

DESCRIPTION

FIG. 1 is a front view of the hood with brim for a garment, wherein the brim is in a flipped-down position.

FIG. 2 is a front-left perspective view of the hood design of FIG. 1, wherein the brim is in a flipped-up position.

FIG. 3 is a front view of the hood design of FIG. 2.

FIG. 4 is a left view of the hood design of FIG. 2.

FIG. 5 is a rear view of the hood design of FIG. 2.

FIG. 6 is a right view of the hood design of FIG. 2.

FIG. 7 is a top view of the hood design of FIG. 2.

FIG. 8 is a bottom view of the hood design of FIG. 2.

FIG. 9 is a front-left view of the hood design of FIG. 1, wherein the brim is in the flipped-down position as in FIG. 1.

FIG. 10 is a front-bottom view of the hood design of FIG. 9.

FIG. 11 is a front view of the hood design of FIG. 9.

FIG. 12 is a left view of the hood design of FIG. 9, wherein a right view of the hood design of FIG. 9 is a mirror image of FIG. 12; and,

FIG. 13 is a rear view of the hood design of FIG. 9.

The cross-hatch shading is fragmentarily shown for convenience of illustration; it being understood that the cross-hatch shading indicates fabric and is uniformly continued over the surface on which it appears.

The evenly spaced broken lines showing a jacket in FIG. 1 illustrate environment and form no part of the claimed design. The evenly spaced broken lines within the bounds of the claimed design illustrate portions of the hood with brim for a garment that form no part of the claim. The dot-dot-dash broken lines indicate the boundary of the claim and form no part thereof.
